United States Patent Office.

S. H. MAPES, OF ALMOND, NEW YORK.

Letters Patent No. 69,457, dated October 1, 1867.

IMPROVED FOLDING BEDSTEAD.

The Schedule referred to in these Letters Patent and making part of the same.

TO ALL WHOM IT MAY CONCERN:

Be it known that I, S. H. MAPES, of Almond, in the county of Alleghany, and State of New York, have invented a new and useful "Folding Bedstead;" and I do hereby declare that the following is a full, clear, and exact description thereof, reference being had to the accompanying drawings, making part of this specification, in which—

Figure 1 is a front elevation of the case, with the bedstead and bed folded, and one side thrown open, with the wash-stand shelf adjusted for use.

Figure 2 is a vertical longitudinal section, showing the case thrown open, and the bedstead to receive the mattress, &c.

Figure 3 is a top of the case and bedstead folded, the top of the case being removed.

Like letters indicate corresponding parts.

This invention consists in connecting the cross-slats to elastic straps that will properly space them when in use, and will contract and fold them when the straps are disconnected in the centre, and in the arrangement of the folding bedstead with a case of peculiar construction for its reception.

To enable others to make and use my invention, I will describe its construction and operation.

I provide a suitable base, A, to which is affixed the back B and the narrow sides S. These are surmounted by the top, having a hinged lid, E. The folding or swinging sections or sides S' are hinged to the sides S, as shown, and the front sections or doors D are hinged to the outer edge of these, as shown in figs. 1 and 3. The case should be made of suitable length and height to receive the width of the bedstead and the height of the head-board. The side rails R are each provided with joints f, g, and h, figs. 2 and 3, the central hinge folding in the opposite direction from the other two, as shown. The rails have an ordinary narrow band, e, attached at the lower edge for the support of the cross-bars b. These bars are attached to the elastic or other suitable ribbons or straps r, which are fastened at one end to the head and to the foot-boards, and one of the end bars or slats is provided at each end with a staple, and the other end bar with a hook, i, to connect the two sections of slats and hold them in their proper relative position when the bedstead is extended, as shown in fig. 2. When the bedstead is to be folded, the slats are unhooked and the two sections are rolled up against the head and foot-boards, which permits the folding of the side rails, as shown in fig. 3. The foot-posts p may be made a trifle longer than the head-posts, if desired, to compensate for the thickness of the base A. They may be provided with casters c, fig. 2. The posts of the head-board H may be secured to the case by a suitable strap, P. There may be ribs or bars J attached to the base to act as guides for the foot-posts, and also as steadyng-bars for the hinged sides S'. The wash-stand shelf G is hinged to the inside of one of the front sections or doors D of the case, and it is provided with a pivoted or hinged brace, k, by which it is held in position, and by removing the foot of the brace from the notch in the door the shelf is folded down as indicated by the dotted lines G', fig. 1. When the bedstead is folded as shown in figs. 1 and 3, the mattress is rolled and secured by two straps, one of which is shown at N, fig. 1, and the pillows and other bed clothing are packed in the space above the bedstead, and the wash-bowl, pitcher, &c., set beneath. The two contiguous edges of the doors may be attached or connected together by a lock or hook, and the lid secured to them in a similar manner.

What I claim as my invention, and desire to secure by Letters Patent, is—

1. Attaching the slats b of each section to the rubber or elastic bands r, which will be more or less stretched when the sections of the slats are to be connected together in the centre, that being done by suitable hooks i, substantially in the manner and for the purposes set forth.

2. The arrangement of the folding bedstead with the enclosing case, composed of the hinged or swinging sections S' and D, and the hinged top E, substantially as described.

S. H. MAPES.
